WILLIAM H. PAGE, OF NORWICH, CONNECTICUT, ASSIGNOR TO WM. H. PAGE & CO., OF SAME PLACE.

Design No. 4,728, dated March 21, 1871.

DESIGN FOR TYPE-BORDER.

The Schedule referred to in these Letters Patent and making part of the same.

I, WILLIAM H. PAGE, of Norwich, in the county of New London, State of Connecticut, have invented and produced a new and original Design of a Border for Printing Purposes, named "Mosaic Border."

The nature of my design is for a border, as shown and described by the accompanying impressions of the border.

It may be printed, as shown, in black, or may have any of the white spaces filled with other colors.

I claim as my invention—

The design for border, as shown.
